SUPPORTING CONSTRUCTION FOR
REGENERATOR BRICKAlbert J. Hulse, Chicago, Ill., assignor to H. A.
Brassert & Company, Chicago, Ill., a corpora-
tion of Illinois

Application June 27, 1930. Serial No. 464,217

2 Claims. (Cl. 72—55)

This invention relates to a new and improved regenerator construction and more particularly to a supporting construction for supporting the regenerator brick.

5 This invention is of particular utility when applied to the support of checkerwork as placed in hot blast stoves of the types used in connection with blast furnaces and the like. The checker column in a hot blast stove of the usual 10 type is from 75 to 100 feet high and is composed of firebrick laid up to form vertical flues. A combustion chamber is provided either in the center or at one side of the stove. The checkerwork is supported upon arches which have openings 15 therebetween communicating with the vertical flues. The gases for combustion together with the necessary amount of air for combustion enter at the bottom of the combustion chamber where combustion takes place. Products of com- 20 bustion flow vertically to the top of the stove and then reverse their flow under the dome and travel downwardly through the checkerwork giving off their heat to the checkerbrick. These products of combustion pass out of the bottom of the stove 25 through a chimney valve into the chimney.

When the stoves are used to give off heat or to preheat air for combustion in the furnaces, the air travels upwardly through the flues in the checkerbrick, thus becoming heated, and passes 30 downwardly through the combustion chamber and out to the furnace. The temperature at the top of the checkers may range from 2000 to 2300 degrees F. in accordance with the quality of the gas used and the efficiency of combustion. The 35 stack temperatures of the products of combustion vary between 300 and 300 degrees F. according to the efficiency of the stove. It usually requires three hours to heat a stove to its maximum temperature and this heat is usually absorbed by 40 the air during a period of one hour. Modern methods of combustion have lengthened the air cycle and shortened the gas cycle and it is theore- 45 tically possible to operate on equal air and gas cycles, although present practice does not approach such operation. In any event, it will be apparent that there are very material and com- 50 paratively rapid temperature changes throughout the stove, and the checkerwork and supporting construction, in the normal operating 55 cycle of the stove. These changes cause the brickwork to expand and contract upon their reversal which causes conditions making the support of the hot and heavy checker column a very difficult problem. Owing to the much smaller 60 coefficient of expansion of metal than that of refractory material, the use of metal in such checkers is much preferable to that of refractory material, although the use of metal has never come generally into practical use.

60 The usual form of checker construction in-

cludes supporting members comprising brick arches superimposed on other brick arches, or in some cases of tiles supported on arches or tiles superimposed upon other tile. Neither the tile nor the brick arch forms of design afford 65 adequate permanent support for the checker column. The tile crack and give way under the weight, while the arches give way due to the movement of the skew-back resulting from the continual expansion and contraction of the 70 brickwork.

According to the present invention, I overcome these difficulties by using metal arches of special design below the brick arches, these metal arches serving both to hold the brick arch elements in 75 place and to support them. These metal arches are preferably made of single pieces of metal specially designed to stand the heat and temperature changes which may be present at their location. The brick arch supported by the metal 80 arch also serves to protect the metal arch against excessive temperatures and violent and rapid temperature changes. Metal members may also be used to provide supports for the superimposed cross arches or cross tiles which are called riders, 85 and are made of the same refractory material as the lower arches. This construction, therefore, avoids detrimental movement between the sup- 90 porting arches and riders, which movement in former constructions has tended to destroy both arches and riders at their points of contact. Suitable packing material between the metal arches and the ring walls and between the arch bricks and supporting metal may be provided for taking 95 care of differences in expansion of the metal and refractory materials. The difference in coefficient of expansion between the metal arch and the superimposed brick arch is also partly com- 100 pensated for by the higher temperature to which the brick arches are exposed and also if uneven expansion between the two arches causes them to settle unevenly, the structure has not been unduly weakened since the brick arch has been 105 designed amply strong to carry the weight of the checker column.

The main purpose of the metal arch is to hold the skew-backs of the brick arches in position so that the arch cannot possibly give way. Another important advantage of my design consists 110 in the fact that where such metal arches are used under the brick arches there is no necessity for the use of any wooden forms in the construction of the brick arches. This results in a considerable saving in the construction of the 115 stove.

It is an object of the present invention to pro- 120 vide a new and improved checkerwork construc- 125 tion comprising metal supports for refractory arches.

It is an additional object to provide a construction of this character in which the metal support is in the form of an arch and carries the refractory arches.

5 It is a further object to provide construction of this character adapted to minimize the wear and breaking away of the refractory arch elements due to heat differences.

10 It is also an object to provide a construction in which the metal supporting elements are protected by the refractory brick work.

Other and further objects will appear as the description proceeds.

15 I have shown certain preferred embodiments of my invention in the accompanying drawings, in which—

Figure 1 is a vertical section through the lower portion of a stove equipped with my invention;

20 Figure 2 is a fragmentary portion of Figure 1 shown on an enlarged scale;

Figure 3 is a plan view of a metal supporting member;

25 Figure 4 is a vertical section through the member of Figure 3;

Figure 5 is a section taken on line 5—5 of Figure 4;

30 Figure 6 is an end view of the construction shown in Figure 4;

Figure 7 is a side view of a metal skew-back construction;

35 Figure 8 is a view of Figure 7 as seen from the right;

Figure 9 is a horizontal section taken on line 9—9 of Figure 7;

40 Figure 10 is a horizontal section taken on line 10—10 of Figure 7; and

45 Figure 11 is a fragmentary plan view showing the relation of the arches.

In the drawings, the furnace shown comprises the outer metal shell 11, the outer ring wall 12 and the inner wall 13 enclosing a combustion chamber 14. The flues leading to and from the combustion chamber form no part of the present invention and are not shown in the drawings.

50 The ports 15 and 16 communicate with the lower portion of the checker chamber 17 which encircles the combustion chamber 14. This checker chamber 17 is filled with checkerwork 18 so placed as to form vertical flues, as clearly indicated in Figure 2. These checkerbrick are supported by the upper arches 19 and lower arches 20 which rest on the ring wall construction 12 and inner wall construction 13, and also on the piers 21. The arches 19 and 20 are formed

55 of a plurality of refractory brick which are tapered in form and the lower arches 20 are directly supported on the metal arches 22. These metal arches are shown in detail in Figures 3 to 6, and are provided with supporting feet 23 resting on the piers and walls, and with upwardly inclined skew-back portions 24 adapted to support the ends of the refractory arch. The arch portion 25 of the member 22 is provided with the strengthening and stiffening web 26. The superimposed arches 19 are not shown as supported on metal arches, but a central double

60 skew-back 27 is located between the two arches, this skew-back being formed of metal and being of a special form as shown. The end skew-backs 28 which support the outer ends of the upper arches 19 may be formed of metal if desired.

The central skew-back 27 is shown in Figures 7 to 10 and is of a particular form for use in stoves having central combustion chambers. Due to the radial arrangement of the arches and the increased circumference between the piers 21 and the outer part of the stove, it is desirable, at least at certain points, to have two arches between the piers 21 and wall 12 abut against a single arch between the piers 21 and inner wall 13 as shown in Figure 11.

80 As shown in Figure 7, the member 27 has lower faces 28 to engage the upper faces of the lower arches 20. It has a bearing face 29 to engage the single arch 19 toward the center of the stove, and spaced bearing faces 30 to engage the spaced outer arches 19. It is also provided with a lug 31 which extends between the faces 30 and serves to properly space the outer arches.

85 It will be apparent that the metal arch members 22 may be placed upon the piers and walls when they have reached the proper height and the checkerwork may be placed upon them without the necessity for the use of any forms or other temporary supporting structure. It will be understood that the arches 19 and 20 are comparatively narrow in width and are spaced apart so as to provide free passage from the lower portion of the stove under the arches to the checkerwork flues which are located above the arches.

90 While this construction is particularly designed for use in hot blast stoves, it may also be adapted for use in supporting other types of checkerwork, such as the checkerwork for open hearth furnaces or heating furnaces of various types. Also, while the construction has been shown in connection with a hot blast stove of the type having a central combustion chamber, it may obviously be used in connection with stoves having chambers located at the sides.

95 While I preferably use cast steel for the lower arch, alloy steels, such as heat resisting steels, can be used to advantage. Where the heat is not excessive, cast iron can be substituted or any other metal may be used provided it is capable of resisting the temperature conditions prevailing at the point of installation.

100 While I have shown one preferred embodiment of my invention by way of illustration, it is capable of being modified to meet varying conditions and I contemplate such changes and modifications as come within the spirit and scope of the appended claims.

105 I claim:

1. In a regenerator construction, a supporting arch comprising a metal arch and a refractory arch, the refractory arch being supported upon the metal arch and the metal arch having end skew-back portions extending upwardly and outwardly across the line of thrust of the refractory arch and thereby taking the end thrust of said refractory arch.

110 2. In a regenerator construction, supporting means comprising superposed arches, the upper arch consisting of a plurality of separate refractory members, the lower arch being a unitary metal structure having integral portions extending substantially normal to the line of thrust of the upper arch and extending across said line and thereby taking the end thrust of the upper arch.

115 ALBERT J. HULSE.
